H. K. ALBUS

CHILD'S VEHICLE

Filed June 8, 1923

INVENTOR.

Harold K. Albus,

BY

Geo. P. Kimmel, ATTORNEY.

UNITED STATES PATENT OFFICE.

HAROLD KESSLER ALBUS, OF ST. JOSEPH, MISSOURI.

CHILD'S VEHICLE.

Application filed June 8, 1923. Serial No. 644,182.

To all whom it may concern:

Be it known that I, HAROLD KESSLER ALBUS, a citizen of the United States, residing at St. Joseph, in the county of Buchanan 5 and State of Missouri, have invented certain new and useful Improvements in Children's Vehicles, of which the following is a specification.

This invention relates to toys and more 10 particularly to coasting toys of the so called "scooter" type.

An object of this invention is the provision of a coasting toy for children, which is so constructed that the child may carry 15 packages thereon without danger of losing or breaking the same.

Another object is to construct the toy in such a manner that the package carrying receptacle may be quickly and easily removed when it is not desired to carry packages therein.

A still further object is the construction of a coasting toy which will be light in weight yet strong, durable and inexpensive 25 to manufacture.

The invention will be best understood from a consideration of the following detail description taken in connection with the accompanying drawing forming part of this 30 specification, with the understanding that the invention is not confined to any strict conformity with the showing of the drawings but may be changed and modified so long as such changes and modifications mark

35 no material departure from the salient features of the invention as expressed in the appended claim.

In the drawings:—

Figure 1, shows a side elevation of the 40 invention, partly in section.

Figure 2, is a front view of the same.

Figure 3, is a top plan view, with the package receptacle removed.

Figure 4, is a longitudinal sectional view 45 of the lower front portion of the complete device.

Figure 5, is a detail sectional view taken on the line 5—5 of Fig. 1.

Figure 6 is a detail showing the upper 50 package receptacle securing means.

Figure 7, is a front elevation of one of the supporting hooks.

Figure 8, is a side elevation thereof.

Figure 9 is a rear elevation of a single 55 supporting member.

Figure 10 is a plan view thereof.

Figure 11, is a rear elevation of a double supporting member and,

Figure 12, is a plan view thereof.

Referring now to the drawings in detail, 60 numeral 1, indicates the platform of the scooter or coasting toy having secured at one end thereof the standard 2, which is constricted near its center forming an upper portion of less width than the lower, the 65 lower portion being of the same width as the platform. The standard has formed transversely of its upper end a channel 2' in which a handle member 4, is secured intermediate its ends by means of the inverted 70 U-strap 5, and bolts 6 and 6', the bolt 6' being passed through the yoke of the strap, through the handle and into the standard between the bolts 6. The standard 2 is secured to the platform 1, by means of a pair of L- 75 shaped angle irons 7, one upon the inner and the other upon the outer sides as shown, suitable bolts 8, being used for securing them in position.

Countersunk in the upper surface of the 80 platform are apertured plate members 9. Through these plate members and the platform beneath pass bolts 10, which retain upon the under surface of the platform, hangers 11, each comprising a plate 11^a secured to the platform, and a central depending, inverted T-shaped arm 11^b, the transverse portion of each arm carrying a wheel 12, thus providing a pair of wheels at the 85 front and back of the platform. 90

When it is desired to carry packages or other articles upon the scooter a receptacle 13, is provided, having the upper half of one side only open as at 14. The receptacle is removably secured to the scooter in 95 the following manner. Upon one side, is provided a series of depending flat tongue members 15 having one end inset at 15' which end is secured to the receptacle by bolts 16, there being a pair of the tongues 100 near the bottom and a single one near the top. Upon the inner face of the standard 2, there are provided a pair of superposed strap members 17, the upper one being inset intermediate its ends to form a single slot when attached to the standard as shown in Fig. 9 and the lower one being inset intermediate its central portion and each end to form a double slot when attached to the standard as shown in Fig. 11, suitable bolts 18, are 110 provided to secure the same to the standard. 105

As shown in Figures 1 and 4 the recep-

tacle is suspended above the platform, it being carried entirely by the standard 2, this method of attachment prevents the receptacle from receiving the severe shocks it 5 would receive were it rested upon the platform, adding greatly to the safety of any fragile articles which might be carried therein.

What I claim is:—

- 10 In a toy of the character described, a relatively long narrow wheeled platform, a handle carrying standard carried thereon, said standard being of the same width at the base as said platform and of less width
- 15 at the central and upper part thereof, a pair of superposed strap members secured to the inner face of said standard, the upper

of said strap members being offset intermediate its ends to provide an upper slot, and the lower of said strap members being offset 20 between its center and each end to provide a pair of lower slots, a package receptacle, a depending tongue member having one end inset for engagement with the upper portion of said receptacle and adapted 25 to engage with its free end said upper slot, and a pair of tongue members having one of their ends offset and secured side by side near the lower portion of said receptacle, and adapted to engage with their free ends 30 said pair of lower slots.

In testimony whereof, I affix my signature hereto.

HAROLD KESSLER ALBUS.
